(57) **CLAIM**

The ornamental design for a vehicular body kit, as shown and described.

DESCRIPTION

FIG. 1 is a front perspective view of the vehicular body kit showing my new design, the vehicle depicted in phantom forming no part of the claimed design;

FIG. 2 is a rear perspective view thereof;

FIG. 3 is a left side elevational view thereof, the right side elevational view being a mirror image of the left side elevational view;

FIG. 4 is a front elevational view thereof;

FIG. 5 is a rear elevational view thereof;

FIG. 6 is a top plan view thereof; and,

FIG. 7 is a front perspective view thereof.

The inner surfaces of the vehicular body kit which normally abut the vehicle do form part of the claimed design.
